CLAIM

The ornamental design for a front door trim assembly for vehicle, as shown and described.

DESCRIPTION

FIG. 1 is a front view of a front door trim assembly for vehicle showing our new design;

FIG. 2 is a left view thereof;

FIG. 3 is a right view thereof;

FIG. 4 is a top view thereof;

FIG. 5 is a bottom view thereof;

FIG. 6 is a perspective view thereof; and,

FIG. 7 is another perspective view thereof.
